HANS TECHEL, OF KIEL, GERMANY, ASSIGNOR TO FRIED. KRUPP AKTIENGESELLSCHAFT GERMANIAWERFT, OF KIEL-GAARDEN, GERMANY.

DEVICE TO ELIMINATE VIBRATIONS DURING ROTATION OF CRANK-SHAFTS IN PISTON-ENGINES WITH MULTIPLE CYLINDERS.

1,359,848.

Specification of Letters Patent. Patented Nov. 23, 1920.

Application filed September 4, 1920. Serial No. 408,375.

To all whom it may concern:

Be it known that I, Dr. HANS TECHEL, residing at Kiel, Germany, a citizen of the German Republic, have invented a certain 5 new and useful Improvement in Devices to Eliminate Vibrations During Rotation of Crank-Shafts in Piston-Engines with Multiple Cylinders, of which the following is a specification.

10 Multiple cylinder piston engines, and more particularly internal combustion engines, used for ships' drift, all possess the disadvantage that vibrations of the crank shafts occur during certain speed, which 15 give rise to unsteady running and fracture.

The object of the present invention is now to eliminate this disadvantage, and the object is attained mainly by supplying a free-moving body, supported by springs, in a 20 casing filled with fluid and rigidly connected with the crank shaft; the relative movement between the casing and the moving body being adjusted by means of a throttling device.

25 In the accompanying drawing is one embodiment of the invention illustrated.

Figure 1 shows a vertical cross-section of the device, and

Fig. 2 a vertical longitudinal section 30 thereof.

An oscillating ring A is mounted to revolve freely on the crank shaft H, having the tendency to turn uniformly during the running. This oscillating ring is surrounded by a casing B, that is rigidly connected with the crank shaft and closed tightly by a cover B'. The oscillating ring A and the casing B are provided with claws a' and b', which mesh in the manner of a 35 claw coupling. Between the claws is, however, enough play provided that spaces C are formed, wherein helical compression springs D are inserted, one end of which abuts against a claw a' of the oscillating 40 ring, and the other end against the claw b' of the casing.

The spaces which are to be found between the casing B and the oscillating ring A are completely filled with a fluid, preferably oil. 45 The two spaces C, situated one on each side of a claw b', are connected with each other by a pipe c'. An adjustable throttle valve E is inserted in this pipe connection, which, according to its adjustment, prevents, more 50 or less, fluid to pass from one space C to

another. The passing of the fluid to the spaces in the casing B takes place continuously, from the pressure conduit J of a pump (not shown), through the passages h', h² of the crank shaft H, and ports a² 60 and passages a³, a⁴, a⁵ in the oscillating ring A.

In order that the fluid which has entered the spaces may not run back and counteract on the pump, back-pressure valves F are 65 inserted in the exit passages a⁵. Lastly, exit ports G, with small, adjustable orifices, are provided in the casing and from which a small part of the fluid may run out continuously.

70 When vibrations, caused by the rotation, occur in the crank shaft H, the casing B must partake in these, because it is rigidly connected with the crank shaft. The oscillating ring A, however, tries to retain its 75 uniform angular velocity. It is, however, prevented from doing this in the same degree as the fluid compressed in the spaces C is restrained, by the throttle valve E, to pass from one space to another. If, for instance, the throttle valve E should be closed 80 tightly and all air driven out, and as the fluid is now compressible, the oscillating ring A must partake in the revolving vibrations of the casing and the entire shaft system. The loose oscillating ring is consequently to be considered as coupled with the 85 shaft.

Should, on the other hand, the throttle valve E be fully open, then the oscillating 90 ring will be able to retain its uniform velocity almost completely; and a relative movement will take place between the loose oscillating ring and the shaft which is rigidly connected with the casing, whereby 95 a certain quantity of fluid will be compressed into one space from another. The magnitude of this relative movement of the loose oscillating ring and the fixed casing is limited, in this case, only through the inserted springs, because no throttling of the 100 fluid occurs. The springs have still another function, namely, at all times to return the oscillating ring to its central position.

With a determined magnitude of the 105 largest oscillations, and by a thereto corresponding adjustment of the throttling valves E, it is possible to create a certain resistance against the revolving vibrations, so that the vibrations are quenched or eliminated before 11

they have had time to develop completely. In this manner is attained the object of diminishing the stresses of the oscillating system.

5. The device is distinguished by its simple construction, its easy adjustment, and the facility with which it may be applied as an addition to old engines.

Claims.

10. 1. In a multiple-cylinder piston engine having a fluid containing casing rigidly mounted on a crank shaft, an oscillating member concentrically mounted in said casing, and flexible connections between said 15 casing and said oscillating member, whereby possible vibrations occurring in said crank shaft may be eliminated.

20. 2. In a multiple-cylinder piston engine having a fluid containing casing rigidly mounted on a crank shaft, an oscillating member concentrically mounted in said casing, and flexible connections between said casing and said oscillating member; said 25 connections comprising alternating projections on said casing and said oscillating member, and springs inserted between said projections.

30. 3. In a multiple-cylinder piston engine having a fluid containing casing rigidly mounted on a crank shaft, an oscillating member concentrically mounted in said cas-

ing, and flexible connections between said casing and said oscillating member; said connections comprising alternating projections on said casing and said oscillating member, and springs inserted between said 35 projections; an adjustable throttle valve for regulating the flow of fluid from one side of said projections to the other.

4. In a multiple-cylinder piston engine 40 having a fluid containing casing rigidly mounted on a crank shaft, an oscillating member concentrically mounted in said casing, and flexible connections between said casing and said oscillating member; said 45 connections comprising alternating projections on said casing and said oscillating member, and springs inserted between said projections; an adjustable throttle valve for regulating the flow of fluid from one side of 50 said projection to the other, a source for compressing fluid, and conduits leading the compressed fluid from the source to said casing; adjustable exhaust ports for said fluid in said oscillating member.

55. The foregoing specification signed at Kiel, Germany.

DR. HANS TECHEL.
